CLAIM

The ornamental design for a protective cap for wooden stake, as shown and described.

DESCRIPTION

FIG. 1 is a perspective view of a protective cap for wooden stake showing my new design;

FIG. 2 is a top view thereof;

FIG. 3 is a bottom view thereof;

FIG. 4 is a front view thereof, the opposite side view being a mirror image thereof; and,

FIG. 5 is a side view thereof.

The features shown in broken lines in FIG. 1 are shown for illustrative purpose only and form no part of the claimed design.
